ENGINE

Application filed August 19, 1931. Serial No. 558,088.

My invention relates to internal combustion engines and more particularly to engines of the sleeve valve type.

In engines of the sleeve valve type it is generally customary to provide a cylinder head for each cylinder of the engine, this cylinder head generally constructed to depend within the cylinder and spaced therefrom to provide a sleeve pocket for receiving the upper end of a suitable sleeve valve means. The combustion chamber is usually formed in the cylinder head and difficulty has been experienced in engine structures of this character in properly sealing the sleeve pocket against the escape of gases from the combustion chamber resulting in loss of pressure and power and also resulting in the accumulation of carbon, rust and other undesirable substances generally referred to as sludge in the sleeve pocket.

An object of my invention is to provide an improved sleeve pocket structure for an internal combustion engine of the sleeve valve type which will effectively overcome the aforesaid difficulties.

Another object of my invention resides in the provision of an improved sealing means for the sleeve pocket which sealing means is capable of manufacture and assembly with the engine at relatively low cost and which will maintain an efficient operation over long periods of use.

A further object of my invention is to provide an improved sealing structure for an engine of the sleeve valve type employing a re-entrant cylinder head spaced from the walls of the cylinder to provide a sleeve pocket accommodating sleeve valve means by constructing a sealing element adapted for movement during the engine power stroke and responsive to pressure developed in the combustion chamber for urging the sealing element in such a manner as to provide a more effective sealing of the sleeve pocket during the engine power stroke.

For a more detailed understanding of my invention reference may be had to the accompanying drawing which illustrates one form which my invention may assume, and in

Fig. 1 is a vertical transverse sectional view through a typical cylinder of an engine of the sleeve valve type and showing my improved sealing structure associated therewith,

Figs. 2 and 3 are enlarged fragmentary sectional views of the sealing structure illustrating the operation of same when subjected to pressures developed in the combustion chamber during the engine power stroke.

Fig. 4 is a plan view of the wedging ring incorporated in my improved sealing structure, and

Fig. 5 is a side elevational view of the wedging ring.

I have preferably illustrated my invention with a sleeve valve engine of the single sleeve valve type which is generally known as the Burt-McCollum engine in which a single sleeve valve, usually operating between the depending cylinder head and cylinder is given a combined reciprocating and oscillating movement with respect to the cylinder and sleeve axes whereby any point on the sleeve traverses a closed path in performing the usual valving cycles of the engine. In the accompanying drawing the illustrated embodiment of my invention shows an engine

A having a cylinder 10 and suitable jacket portions 11 through which a cooling medium may be circulated. A cylinder head 12 is secured to the engine block and is provided

with a portion 13 depending within the cylinder 10 and spaced therefrom to provide a sleeve pocket 14 adapted to accommodate the upper end of suitable sleeve valve means 15.

The cylinder head is preferably provided with a combustion chamber 16 and the spark plug or other ignition device 17 is supported by the cylinder head in the usual manner.

The sleeve valve means is provided with intake and exhaust ports 18 and 19 respectively which are constructed and arranged to respectively cooperate with the cylinder intake and exhaust ports 20 and 21. A piston 22

operates within the cylinder and preferably within the sleeve valve means and is adapted for connection with the engine crankshaft (not shown) by means of the usual connecting rod 23.

As stated in the introductory paragraphs of the specification, my invention is particularly related to the means for sealing the sleeve pocket for preventing the escape of pressure and the accumulation of undesirable sludge within the sleeve pocket. The sleeve pocket may be efficiently sealed by the employment of a yieldable cylindrical sleeve 25, this ring being preferably cylindrical and 5 adapted for insertion between the depending portion 13 of the cylinder head and the sleeve valve means 15. This cylindrical sleeve 25 is preferably constructed of thin metallic material such as brass, or other suitable material 10 of like characteristics and the same is preferably secured to the cylinder head by crimping the upper edge of the cylindrical sleeve 25 within a groove 26 carried by the cylinder head as at 27. The cylindrical sleeve 25 preferably depends adjacent the outer cylindrical walls of the depending portion 13 of the cylinder head and contact therewith for substantially the full length of the sleeve. It will be noted that this cylindrical sleeve 25 is capable of movement radially outwardly 15 with respect to the cylinder head for normally effecting a sealing engagement with the sleeve valve means 15. The lower edge of the cylindrical sleeve 25 is preferably turned inwardly to provide an inwardly extending flange 28 for a purpose which will be hereinafter made apparent. The lower portion of the re-entrant cylinder head 14 is preferably reduced in diameter as at 29 and provided with 20 an inwardly extending tapered portion 31. A wedging ring 30 is adapted for assembly within the reduced portion of the cylinder head and this wedging ring is preferably provided with an inner surface 32 provided 25 with a taper corresponding to the taper of the lower portion of the cylinder head, and the outer circumferential surface of the wedging ring is adapted for engagement with the lower portion of the cylindrical sleeve 25.

It will be noted that the lower face of the wedging ring is subjected to any pressures developed within the combustion chamber of the engine and these pressures are developed 30 during the power stroke of the engine. Thus the pressures developed during the engine power stroke act upon the wedging ring and tend to force the same from a position shown in Fig. 3 to that shown in Fig. 2, said co-operating tapered portions of the ring and cylinder head acting to expand the ring which is split as at 33 and thereby expand 35 the lower portion of the cylindrical sleeve or sealing element during the engine power stroke. The expanding of this cylindrical sleeve 25 provides a more effective sealing engagement between the sealing element or sleeve 25 and the sleeve valve means 15 during the engine power stroke.

Experience has shown when operating engines of the sleeve valve type that the pres-

sure loss due to inefficient sealing structures for the sleeve pocket are more detrimental to the engine operation at low engine speeds than at high engine speeds. It has been found that the power loss at low engine speeds is quite excessive unless some means are provided for sealing the sleeve pocket effectively. Many devices have been proposed for obtaining this result but such devices have been constructed to act throughout the cyclical events of the engine operation and thus the frictional losses were found to more than overcome the advantages gained by use of such sealing structures. In my device I provide a sealing structure in which frictional losses are maintained at a minimum due to the fact that the sealing element is urged into a more efficient sealing engagement only during the engine power stroke, and when the pressure acting on said sealing element is relieved during the other cyclical events of the engine operation the friction between the sealing element and the engine sleeve valve is reduced to a minimum, thereby permitting the operation of the sleeve valve means with a minimum of frictional losses.

The construction as described and illustrated above provides for improved engine performance with a minimum of power loss throughout a range of engine speeds. Furthermore the structure shown in the illustrated embodiment of my invention can be economically manufactured and readily assembled with an engine of the character as specified above with a minimum of expense. Also, the structure as herein described may be readily serviced with a minimum of expense thereby providing an engine structure which will give satisfactory performance throughout its life and due to the efficient operation of my device it may be noted that frequent removal of carbon or sludge deposits in the sleeve pocket which necessitate the removal of the cylinder heads are unnecessary since my device is very effective in preventing such accumulations of sludge or other undesirable deposits within the sleeve pocket of the engine.

Although I have illustrated but one form of my invention and have described in detail but a single application thereof, it will be apparent to those skilled in the art to which my invention pertains that various modifications and changes may be made therein without departing from the spirit of my invention or from the scope of the appended claims.

What I claim as my invention is:

1. In an engine, a cylinder, a structure closing the cylinder and having a portion depending within and spaced from the cylinder, valve means operable in the space provided between said structure and cylinder, a sealing element associated with said structure for sealing said space, and means mov-

ably supported in juxtaposition with said sealing element and subjected to pressure developed during the engine power stroke for increasing the effectiveness of said sealing element during the engine power stroke.

2. In an engine, a cylinder, a structure closing the cylinder and having a portion depending within and spaced from the cylinder, valve means operable in the space provided between said structure and cylinder, a yielding sealing element associated with said structure for sealing said space, and means movably supported for engagement with said sealing element and subjected to pressure developed during the engine power stroke for urging said sealing element into a more effective sealing engagement with the valve means during said engine power stroke.

3. In an engine, a cylinder, a structure closing the cylinder and having a portion depending within and spaced from the cylinder, valve means operable in the space provided between said structure and cylinder, a sealing element associated with said structure for sealing said space, and a wedge member engaging said sealing element and subjected to pressure developed during the engine power stroke for urging said sealing element into a more effective sealing position within said space.

4. In an engine, a cylinder, a structure closing the cylinder and having a portion depending within and spaced from the cylinder, valve means operable in the space provided between said structure and cylinder, a sealing element associated with said structure for sealing said space, and a ring like wedge member subjected to pressure developed during the engine power stroke for urging said sealing element into a more effective sealing position within said space.

5. In an engine, a cylinder, a structure closing the cylinder and having a portion depending within and spaced from the cylinder, valve means operable in the space provided between said structure and cylinder, an expansible sealing element associated with said structure and adapted for engagement with said valve means for sealing said space, and means movably supported in engagement with said element and subjected to pressure developed during the engine power stroke for expanding said sealing element and urging same into a more effective sealing engagement with the valve means during the engine power stroke.

6. In an engine, a cylinder, a structure closing the cylinder and having a portion depending within and spaced from the cylinder, valve means operable in the space provided between said structure and cylinder, an expansible sealing element associated with said structure and adapted for engagement with said valve means for sealing said space, and a wedge member engaging said

element and subjected to pressure developed during the engine power stroke for urging same into a more effective sealing engagement with the valve means during the engine power stroke.

7. In an engine, a cylinder, a structure closing the cylinder and having a portion depending within and spaced from the cylinder, valve means operable in the space provided between said structure and cylinder, a sealing element for sealing said space and secured at its upper edge to said structure, and means movably supported in engagement with the lower portion of said element and subjected to pressure developed during the engine power stroke for urging said sealing element into a more effective sealing engagement with the valve means during the engine power stroke.

8. In an engine, a cylinder, a structure closing the cylinder and having a portion depending within and spaced from the cylinder, valve means operable in the space provided between said structure and cylinder, and expansible sealing element for sealing said space and secured at its upper edge to said structure, and a wedge member engaging the lower portion of said element and subjected to pressure developed during the engine power stroke for expanding said sealing element into a more effective sealing engagement with the valve means during the engine power stroke.

9. In an engine, a cylinder, a structure closing the cylinder and having a portion depending within and spaced from the cylinder, valve means operable in the space provided between said structure and cylinder, a sealing element for sealing said space and comprising an expansible sleeve supported intermediate said structure and said valve means, and means movably supported in engagement with said sleeve and subjected to pressure developed during the engine power stroke for expanding said sleeve and urging same into a more effective sealing engagement with the valve means during the engine power stroke.

10. An engine of the sleeve valve type comprising in combination, a cylinder, a cylinder head providing a combustion chamber and depending within and spaced from the cylinder, sleeve valve means operable in the space provided between said cylinder head and cylinder, a sealing element associated therewith for sealing said space, and means movably supported in engagement with said sealing element and subjected to pressure developed in the combustion chamber during the engine power stroke for urging said sealing element into a more effective sealing engagement with the sleeve valve means during the engine power stroke.

11. An engine of the sleeve valve type comprising in combination, a cylinder, a cyl-

- inder head providing a combustion chamber and depending within and spaced from the cylinder, sleeve valve means operable in the space provided between said cylinder head and cylinder, a cylindrical sealing element associated therewith for sealing said space, and means movably supported in engagement with said sealing element and subjected to pressure developed in the combustion chamber during the engine power stroke for urging said cylindrical sealing element into a more effective sealing engagement with the sleeve valve means during the engine power stroke.
12. An engine of the sleeve valve type comprising in combination, a cylinder, a cylinder head providing a combustion chamber and depending within and spaced from the cylinder, sleeve valve means operable in the space provided between said cylinder head and cylinder, a cylindrical sealing element for sealing said space and secured adjacent its upper edge to said cylinder head, and means movably supported in engagement with the lower portion of said element and subjected to pressure developed in the combustion chamber during the engine power stroke for urging said cylindrical sealing element into a more effective sealing engagement with the sleeve valve means during the engine power stroke.
13. An engine of the sleeve valve type comprising in combination, a cylinder, a cylinder head providing a combustion chamber and depending within and spaced from the cylinder, sleeve valve means operable in the space provided between said cylinder head and cylinder, a cylindrical sealing element for sealing said space and secured adjacent its upper edge to said cylinder head, and a wedge ring between said element and cylinder head and subjected to pressure developed in the combustion chamber during the engine power stroke for urging said cylindrical sealing element into a more effective sealing engagement with the sleeve valve means during the engine power stroke.
14. An engine of the sleeve valve type comprising in combination, a cylinder, a cylinder head providing a combustion chamber and depending within and spaced from the cylinder, sleeve valve means operable in the space provided between said cylinder head and cylinder, a cylindrical sealing element for sealing said space and secured adjacent its upper edge to said cylinder head, and a wedge ring between said element and cylinder head and subjected to pressure developed in the combustion chamber during the engine power stroke for expanding said cylindrical sealing element radially outwardly into a more effective sealing engagement with the sleeve valve means during the engine power stroke.
15. An engine of the sleeve valve type com-

prising in combination, a cylinder, a cylinder head providing a combustion chamber and depending within and spaced from the cylinder, sleeve valve means operable in the space provided between said cylinder head and cylinder, a cylindrical sealing element intermediate the cylinder head and sleeve valve means, said sealing element being secured at its upper edge and depending therefrom in engagement for the most part with the cylinder head but radially movable therefrom, and means supported adjacent the lower edge of said element between said cylinder head and sleeve valve means and subjected to pressure developed in the combustion chamber during the engine power stroke for urging said sealing element into a more effective sealing engagement with the sleeve valve means during the engine power stroke.

16. An engine of the sleeve valve type comprising in combination, a cylinder, a cylinder head providing a combustion chamber and depending within and spaced from the cylinder, sleeve valve means operable in the space provided between said cylinder head and cylinder, a cylindrical sealing element intermediate the cylinder head and sleeve valve means, said sealing element being secured at its upper edge and depending therefrom in engagement for the most part with the cylinder head but radially movable therefrom, and a wedging ring supported adjacent the lower edge of said element between the cylinder head and sleeve valve means and subjected to pressure developed in the combustion chamber during the engine power stroke for urging said sealing element into a more effective sealing engagement with the sleeve valve means during the engine power stroke.

17. An engine of the sleeve valve type comprising in combination, a cylinder, a cylinder head providing a combustion chamber and depending within and spaced from the cylinder, sleeve valve means operable in the space provided between said cylinder head and cylinder, a cylindrical sealing element intermediate the cylinder head and sleeve valve means, said sealing element being secured at its upper edge and depending therefrom in engagement for the most part with the cylinder head but radially movable therefrom, and a split wedging ring engaging the lower portion of said element and supported intermediate the cylinder head and sealing element, said ring and cylinder head having cooperating tapered interengaging surfaces, said ring subjected to pressure developed in the combustion chamber during the engine power stroke whereby by reason of said cooperating tapered surfaces, said ring urges said sealing element into a more effective sealing engagement with the sleeve valve means during the engine power stroke.

18. An engine of the sleeve valve type com-

prising in combination, a cylinder, a cylinder head providing a combustion chamber and depending within and spaced from the cylinder, sleeve valve means operable in the space
5 provided between said cylinder head and cylinder, a cylindrical sealing element intermediate the cylinder head and sleeve valve means, said sealing element secured at its upper edge to said cylinder head and de-
10 pending therefrom in engagement with the cylinder head but radially movable therefrom and provided with an inwardly ex-
tending flange at its lower edge, and a split wedging ring engaging the lower portion of
15 said element and supported by said inwardly ex-
tending flange, said ring subjected to pres-
sures developed in the combustion chamber
during the engine power stroke for urging
20 said sealing element into a more effective
sealing engagement with said sleeve valve
means during the engine power stroke.

In testimony whereof I affix my signature.
